UNITED STATES PATENT OFFICE

141,158

DESIGN FOR A RAINCOAT OR SIMILAR ARTICLE

Egon Bernath, New York, N. Y.

Application February 5, 1945, Serial No. 117,772

Term of patent 3½ years

(CL. D3—4)

To all whom it may concern:

Be it known that I, Egon Bernath, a citizen of the United States, residing at New York city, in the county and State of New York, have invented a new, original, and ornamental Design for a Raincoat or Similar Article, of which the following is a specification, reference being had to the accompanying drawing, forming part thereof.

Fig. 1 is a front view of a raincoat or similar article, showing my new design.

Fig. 2 is a rear view thereof.

The dominant feature of the design resides in the portions shown in full lines.

I claim:

The ornamental design for a raincoat or similar article, substantially as shown and described.

EGON BERNATH.
